US0D1052757S

(12) **United States Design Patent** (10) Patent No.: **US D1,052,757 S**
(45) Date of Patent: ** Nov. 26, 2024

(54) **WINDOW**

(71) Applicant: **VKR Holding A/S**, Hørsholm (DK)
(72) Inventors: **Asbjørn Skyum Blichfeldt**, Hørsholm (DK); **Rasmus Fogelberg Skov**, Hørsholm (DK)
(73) Assignee: **VKR Holding A/S** (DK)
(**) Term: **15 Years**
(21) Appl. No.: **35/519,340**
(22) Filed: **Sep. 29, 2023**

(80) **Hague Agreement Data**

Int. Filing Date: **Sep. 29, 2023**
Int. Reg. No.: **DM/233455**
Int. Reg. Date: **Sep. 29, 2023**
Int. Reg. Pub. Date: **Dec. 15, 2023**

(30) **Foreign Application Priority Data**

Mar. 30, 2023 (EM) 015016376-0001
Mar. 30, 2023 (EM) 015016376-0002
Mar. 30, 2023 (EM) 015016376-0003

(51) LOC (14) Cl. **25-02**

(52) U.S. Cl.

USPC **D25/48.7**

(58) **Field of Classification Search**

USPC D25/47.1, 48.1, 48.3, 48.4, 48.5, 48.6, D25/48.7, 48.8

CLAIM

The ornamental design for a window as shown and described.

DESCRIPTION

- 1.1 - Rear, top, left perspective
  - 1.2 - Front, bottom, right perspective
  - 1.3 - Front view
  - 1.4 - Rear view
  - 1.5 - Bottom view
  - 1.6 - Top view
  - 1.7 - Right side (same as left side)
  - 2.1 - Front, top, right perspective
  - 2.2 - Rear, bottom, left perspective
  - 2.3 - Front view
  - 2.4 - Rear view
  - 2.5 - Top view
  - 2.6 - Bottom view
  - 2.7 - Left side (same as right side)
  - 3.1 - Front, top, right perspective
  - 3.2 - Rear, bottom, left perspective
  - 3.3 - Front view
  - 3.4 - Rear view
  - 3.5 - Bottom view
  - 3.6 - Top view
  - 3.7 - Right side (same as left side)
- A window in a supply position, a window in a mounted position, and a window in a position of use.
